UNITED STATES PATENT OFFICE.

HENRY H. SCHAEFER, OF WELDONA, COLORADO.

WIRE TIGHTENER AND SPLICER.

1,400,995.

Specification of Letters Patent. Patented Dec. 20, 1921.

Application filed February 19, 1921. Serial No. 446,374.

To all whom it may concern:

Be it known that I, HENRY H. SCHAEFER, a citizen of the United States, residing at Weldon, in the county of Morgan and State of Colorado, have invented certain new and useful Improvements in Wire Tighteners and Splicers, of which the following is a specification, reference being had to the accompanying drawings.

10 This invention relates to means for tightening wires, and particularly to means whereby the broken ends of a wire, as for instance the broken ends of a fence wire, may be drawn together and spliced.

15 The general object is to provide a machine of this character which is very simple in its construction, which may be cheaply made, and which is thoroughly effective for the purpose intended.

20 A further and more specific object is to provide means whereby the wires may be kept under tension and not allowed to become slack while the loop is being formed and twisted.

25 Another object is to provide a construction of this character which is adapted for use in tightening strands of a barbed wire fence and connecting or twisting said strands together.

30 Other objects will appear in the course of the following description.

My invention is illustrated in the accompanying drawings, wherein:

35 Figure 1 is a side elevation of my wire stretcher and splicer;

Fig. 2 is a top plan view of the construction shown in Fig. 1;

40 Fig. 3 is a longitudinal sectional view of the stretcher and splicer showing the parts in their initial position;

Fig. 4 is a like view to Fig. 3 but showing the sections folded upon each other to form the bight in the wire X;

45 Fig. 5 is a like view to Fig. 4 but showing the manner in which the wire is twisted;

Fig. 6 is a detailed elevation of the frame showing the means for holding the main winding shaft from reverse rotation;

50 Fig. 7 is a longitudinal section of a modified form of the machine.

In Figs. 1 to 6, I show one form of my invention, and it will be seen that the tightening and twisting device comprises two sections designated generally A and B. The 55 section A consists of two parallel bars 10 joined to each other in any suitable manner

so as to form an approximately U-shaped yoke and extended, as at 11, at the closed end of the yoke to any suitable extent. The two parallel bars or legs of this approximately U-shaped yoke are connected at 12 by a cross bar, this cross bar being preferably integral with the bars 10 but being depressed below the level of said bars. On the extension 11 or shank of the section A 60 there is provided a wire clamp comprising a cam-shaped or eccentric clamping member 13 and a transversely curved flange 14 with which the clamping member 13 engages. Any suitable wire clamping member may be 65 used in place of the parts 13 and 14 but such a clamping means as that illustrated has been found to be thoroughly effective in practice and extremely simple.

The section B comprises two parallel bars 75 15 which are angularly bent, as at 16, and joined by a cross bar, as at 17, these two bars 15, the angular bend 16 and the cross bar 17 being preferably formed in one piece. The extremities of the bar 15 opposite the 80 bend 16 are formed with a transversely extending head 17 formed at its ends to provide trunnions 18 inserted and oscillatable in apertures 19 formed in the arms 10 of the section A. This head 17 is formed with a 85 pair of upwardly extending lugs 20 which extend outward from the bars 15 and toward the bend 16. These lugs constitute hooks adapted to engage with a loop of wire 90 formed on one of the lengths of wire to be joined. I do not wish to be limited to the particular manner of pivotally connecting the section B to the section A, as other means of pivotally connecting these sections can be used.

95 Rotatably mounted within the section A and specifically between the bars 10 of the section A is a winding shaft or drum 21 which is formed at one end with a trunnion 22 to extend through a bearing aperture 100 formed in one of the bars 10, and its opposite end extends through and is rotatable within the other bar 10. This shaft or drum 21 is preferably formed integral with a gear wheel 23. Also rotatably mounted in the 105 bars 10 is a transverse shaft 24 carrying preferably an integral gear wheel 25 which engages the gear wheel 23, the gear wheel 25 being of relatively small diameter in comparison with the gear wheel 23. The 110 opposite end of the shaft 24 is squared or otherwise formed to carry the crank 26, and

mounted upon one end of the shaft is a ratchet wheel 27 with which a pawl 28 co-acts, preventing reverse movement of the winding drum and of the shaft 24 under strain. Preferably that portion of the section B which extends upward, as at 16, is formed with an upwardly and laterally projecting supporting lug 29 upon which the wire which passes through the upwardly extending U-shaped portion 16 is disposed.

The operation of this form of my invention is as follows: The machine is first folded, as in Fig. 4. A loop is formed on the end of a length of wire X and over the hooks 20 in part B, the wire to be one of the broken strands of the fence. The machine is then unfolded, as in Fig. 3, and wire X is passed between cam clamp 13 and the flange 14. Of course, the wire is anchored at one end. The opposite length of wire Z is now passed through to the upwardly extending loop 16 and through an aperture 30 formed in the rotatable winding drum 21. Then part B is pulled down and the wire Z is hooked over support 29. Any suitable means may be used for engaging this length of wire Z with the winding drum and I have merely illustrated the slot 30 or aperture for the sake of illustration. The winding drum is then rotated, by rotating the crank handle 26, until the wires are taut. Then the clamp composed of the parts 13 and 14 is released from the wire X and the section A is lifted and turned over until the loop Y slips from the hooks 20 onto the wire Z. The whole device is now supported by the section A and the wire X and its loop Y, and if now a turning movement be given to the mechanism around the axis of the wire Z, that portion 40 of the wire Z between its point of engagement with the loop Y and the drum 21 will be bent to form a loop and wrapped around the wire Z. As the machine is turned around the axis of the wires X and Z, it is gradually shifted from a position nearly parallel to the axis of the wires to a position at right angles thereto and thus a loop is formed substantially of the form shown in Fig. 5. After the wire has been fully tightened and the loop sufficiently twisted, that portion of the wire Z which is disposed between the drum 21 and the loop is cut off by wire nippers, thus releasing the mechanism from the fence wire and leaving the two lengths X and Z of the fence wire perfectly tight but joined together by interengaging loops.

The purpose of the cross bar 12 is to keep the ends of the bars 10 of section A from pulling together under heavy strain and this bar also holds the loop Y at such an angle to the wire Z going through it that the barbs of the wire, if a barbed wire fence is being mended, do not catch on the top of the loop. After the wire has been tightened the part A

folds over upon part B and the loop Y is drawn off the lugs 20 at just the right time so that there is no slack lost and the wire Z, the end of which is attached to the drum 21, is practically bent double over the wire of 70 the loop Y so that it holds without slackening while the splice is being completed by rotating the mechanism around the longitudinal axis of the wires Y and Z. The ability of this machine to fold the wire Z over and 75 around the loop Y and the subsequent release of the loop Y from the lugs 20 I regard as the important and basic feature of this machine, as thereby no slack is lost when the splice is being made. Another vital feature 80 of the invention is the means whereby the loop in the wire Z is formed by winding the wire from the winding drum or spool and between the loop around the main wire Z. The supporting finger 29 is of importance, 85 in that it goes nearly across the space in the angular part 16 and is inclined forward so that it may be placed under the wire to keep the end 16 of the section B from flying upward under strain. It is inclined forward 90 and upward so that the barbs of wire will readily slip over it. I do not wish to be limited to the exact form and construction of this part of the device, however, as other means might be used for guiding the wire 95 at this point and preventing the end 16 of the section B from flying up under strain.

It will be seen that the turning of the section A over upon the section B causes the wire Z to be bent upon itself and form a 100 bight around the loop Z without slackening the wire, and that if now the machine as a whole be rotated around the axis coinciding with the wires X and Y, the winding drum or shaft 21 will be carried around this axis 105 and will cause that portion of the wire between the end of the bight and the drum to be wrapped around the wire Z, thus forming a close loop engaging with the loop Y. When the section A is turned over upon the 110 section B, the strain on the wire Z causes the loop Y to slip from the hooks formed by the lugs 20. My invention broadly consists, therefore, in the provision of a tightening and wire twisting device which consists in 115 two sections pivoted to each other for movement into or out of alining relation, one of the sections being provided with a wire tightening device and the other with a loop holding device, the sections being pivoted to 120 each other so that they may be turned into a position to bend the wire Z to form a bight around the loop Y, both of said sections being so mounted that they may be rotated bodily around the axis formed by the wires 125 Y and Z to thereby place the end of the bight of the wire Z around the body of the wire to form a second loop in the wire.

In Fig. 7, I show a modification of the construction which has just been described 130

which operates on just exactly the same principle as this construction but which differs from this construction in that the hooks, designated 20^a in Fig. 7, are disposed in such manner that initially the parts are folded and then the parts are unfolded to take off the loop Y from these hooks and form the bight. Inasmuch as the construction is otherwise the same as that illustrated in Figs. 1 to 6, no further description of this modification is believed to be necessary.

It is to be particularly noted that in the construction shown in Figs. 1, 2 and 3 and in the construction shown in Fig. 7, the bight of the hook 20 or 20^a is radially distanced from the axis of the two sections 18 and that particularly the bight of the hooks 20 or 20^a is normally disposed nearer to the tensioning device than the axis of the sections. Thus in Figs. 1 and 3 where the parts are disposed in their normal position, the cross bar of the loop Y is disposed nearer to the tensioning device 21 than the pivot 18 so that when the parts are turned to the position shown in Fig. 4 the tension on the wire Z will cause the loop Y to draw away from the bight of the hooks 20 beyond the bills thereof so that then the bill 20 will escape from the loop when the wire 30 tightener is turned to form the coil on the wire Z. The same is true in Fig. 7, which shows this modification of the wire tightener in its normal position. Here it will be seen that the bight of the hooks 20^a is disposed nearer to the tensioning device 21 than is the pivotal axis of the sections A and B and that when the section A is turned into alinement with the section B the loop Y will be drawn off of the hooks 28. It will be noted that the finger 29 prevents the section B in Fig. 3 from being drawn upward by the pull on the loop Y, which would act to lower the loop Y. As is illustrated, the loop Y is disposed at an angle 45 to the wire Z so as to permit the ready passage of the wire Z through the loop Y.

I claim:—

1. A wire tightener and splicer comprising two sections, one of said sections having thereon a pair of laterally spaced, loop engaging hooks, the other section having a wire tightening device, the loop engaging hooks having their bills normally extending from the tensioning device, the last named section being pivoted to the first named section on an axis radially distant from the bight of the hooks and disposed normally a greater distance from the tensioning device than the bight of said hooks whereby to cause the loop to be pulled from said hooks when the wire on the second named section has been bent around said loop.

2. A wire tightener and splicer comprising two sections, one of said sections being approximately U-shaped in form to provide

a cross bar and two arms, the cross bars being disposed in off-set relation to the two arms, said section having a finger extending from the cross bar, the opposite ends of the arm being formed with wire loop supporting hooks, the other section having a wire tensioning device and the loop engaging hooks having their bills normally extending away from the tensioning device, the last named section being pivoted directly to said arms at a point radially distant from the bight of the hooks and normally a greater distance from the tensioning device than the bight of the hooks whereby to cause the loop to be drawn from said hooks when the wire carried on said section has been bent around said loop.

3. A wire tightener and splicer comprising two sections, one of said sections having thereon adjacent one end a pair of rearwardly turned loop engaging hooks, the other section having thereon a winding drum, and means for rotating the winding drum, the last named section being pivoted to the first named section adjacent said hooks whereby the sections may be turned into or out of an approximately alined relation as and for the purpose set forth.

4. A wire tightener and splicer comprising two sections, one of said sections having at one end a pair of spaced rearwardly projecting wire supporting hooks, the opposite end having an upwardly projecting loop with a supporting finger, the other section having a wire tightening drum mounted thereon midway of its length and having means whereby the drum may be rotated and carrying at its end wire clamping means, said sections being pivoted to each other adjacent said hook whereby a wire passed through the loop and engaged by said tightening drum may be bent upon itself to form a bight, the two sections being bodily rotatable upon the axis of the connected wires to thereby wrap the end of the bight around the body of the wire.

5. A wire tightener and splicer comprising two sections, one of said sections comprising a pair of spaced, longitudinally extending bars connected at one end, said connected portion of the bars being bent at right angles and formed with an outwardly and an upwardly projecting finger, the opposite ends of said bars being formed to provide rearwardly extending, loop engaging hooks, the other section being formed of two connected, parallel bars pivoted to the first named section adjacent said hooks and having a transverse cross bar, a winding drum journaled between the bars of the second named section outward of said cross bar and having means whereby the winding drum may be rotated, and a wire clamp mounted upon the end of the second named section.

6. A wire tightener and splicer formed of

two sections, one of said sections comprising two parallel bars connected at one end, the connected end of this section being angularly bent and formed with a projecting wire supporting finger, the opposite ends of said bars being formed to provide rearwardly extending hooks, the other section being formed of two parallel, connected bars pivoted at one end to the other section adjacent said hooks, a winding member mounted upon the second section and having a gear wheel, a crank shaft mounted upon the second section and having a gear wheel engaging the first named gear wheel whereby the winding member may be rotated, and a cross bar extending across the space between the two first named bars and the last named section between the winding drum and the pivotal axis of the sections, the outer end 20 of the second named section carrying a wire clamping device.

7. A wire tightener and splicer formed of two sections, one of said sections comprising spaced, longitudinally extending bars, the

bars being connected to each other at one end 25 and the connected end being angularly bent and formed with a wire supporting finger, the opposite ends of the bars being connected by a transversely extending head formed with trunnions and formed to provide rearwardly projecting, loop engaging hooks, a second section formed of two parallel bars connected at their outer ends, the inner ends of the bars being formed with bearing apertures for engagement with said 30 trunnions, a winding drum mounted in said parallel bars for rotation therein and carrying a gear wheel, a crank shaft passing through said bars and carrying a second gear wheel engaging the first named gear wheel, 40 and a cross bar connecting the parallel bars of this section and disposed between the winding drum and the pivotal axis of the sections, said cross bar being depressed below the level of the longitudinal bars. 45

In testimony whereof I hereunto affix my signature.

HENRY H. SCHAEFER
